UNITED STATES PATENT OFFICE.

WILLIAM LAWRENCE MURPHY, OF BOSTON, MASSACHUSETTS.

ADJUSTABLE BLACKBOARD-LINER.

SPECIFICATION forming part of Letters Patent No. 623,805, dated April 25, 1899.

Application filed November 21, 1898. Serial No. 696,969. (No model.)

To all whom it may concern:

Be it known that I, WILLIAM LAWRENCE MURPHY, of South Boston, in the county of Suffolk and State of Massachusetts, have invented certain new and useful Improvements in Adjustable Blackboard-Liners, of which the following is a description sufficiently full, clear, and exact to enable those skilled in the art to which it appertains or with which it is most nearly connected to make and use the same.

My invention comprises an improved staff-marker and is intended to provide a simple and efficient means for holding crayons or the like for drawing a series of parallel or concentric lines, provision being made for adjusting the extent of space or distance between the lines.

It is particularly adapted for quickly marking musical staves upon a blackboard, as well as for ruling the different sets of columns used in bookkeeping. It is also adapted for general use in geometrical drawing.

In the the accompanying drawings I have shown forms in which I may embody my invention.

Figure 1 is a side elevation of my device, a portion of the stock or head being broken away to show the shoulders or stops. Fig. 2 is a similar view taken at right angles to the plane of Fig. 1, a portion being represented as in section. Fig. 3 is a side elevation of a modified form of the invention. Fig. 4 is a plan view of the guiding and rest roller and its immediate equipments.

The marker, as shown, comprises a suitable base or stock *a*, having projecting from one side thereof a handle *b* and having also a series of arms *d* projecting from the opposite side. These arms *d* are made of thin flexible resilient material, as sheet metal, so that they bend easily under pressure for a purpose to be hereinafter explained.

Near their outer ends the arms are formed with resilient fingers *f*, arranged to form a resilient clamp for holding crayons or the like. Said fingers *f* may be flared at their inner and outer ends to facilitate the ready insertion of the crayons.

The arms *d* are pivoted upon bolts or studs *e*, so that they may be swung to and fro in the same plane in order to secure any desired adjustment with relation to one another.

I have shown the stock or base recessed, as at *c*, to form shoulders *d'*, which serve as stops 55 to limit the pivotal movement of said arms, although any suitable form of stop may be used for this purpose. These stops may of course be formed at any predetermined distance from the perpendicular line passing 60 through the pivotal center, so that the distance between two adjacent arms may be accurately determined when the arms are resting against the stops.

By having both ends of the fingers flared 65 the crayon shown in dotted lines at *g* may be inserted from either end. The spring of the jaws or fingers *f* should be sufficiently strong to retain the crayon without slipping and yet resilient enough to permit the ready removal 70 or insertion of the crayon.

I have shown a metallic band *l* passing around the edge of the stock, which serves to cover up the recesses. The tightening of the screws *e*, moreover, serves to cause this band 75 to bind upon the ends of the arms *d*, so that said arms may not be displaced from their proper position when in use.

My object in making the arms flexible and resilient is to compensate for any unevenness 80 in the relative position of the crayons due to unequal wear or inexact alinement. Thus if one of the crayons should project beyond the line of the others it would not cause any inconvenience, since the arm would readily 85 bend back until this difference in length was compensated for without in any way interfering with the parallelism of the line made by it in reference to the line made by the other crayons.

As shown in Fig. 1 of the drawings, the arms are in proper position to mark out a musical staff. If it is desired to rule a set of columns for bookkeeping, the arms can be adjusted into proper relationship to rule off any desired set of columns. Owing to the disposition of the handle *b* it is easy to swing the device about one of the crayons as a center and thus form concentric circles. The extent of its use for geometrical blackboard-work is 100 very great.

In Fig. 3 I have shown the staff-marker as provided with a rest and guiding-roller *r*, which may be covered with rubber *s* or be otherwise suitably constructed, which roller 105 is connected with the stock or head *a* through

the medium of the shank *t*, projecting from the ears or clips *u*, which form bearings for the journal-pins *v* of the roller. When the device is equipped with the roller, as shown, 5 straight parallel lines may be drawn upon a board or other thing without the aid of a ruler.

While all of the arms *d* may be made adjustable, in some cases the central arm may be made rigid and the others made adjustable 10 with respect to the central one, so that the space between the lines drawn may be rendered wider or narrower, as may be desired.

The screws *e* may be turned down so tightly as to hold the arms *d* in any position to which 15 they may be adjusted, the shoulders *d'* only limiting the extent of adjustment.

It is to be noted that the arms *d* are inherently resilient—that is, they are inherent spring-arms and not arms controlled by 20 springs. In the latter case they would be more cumbersome, less sensitive, and more uncertain of action than in the former.

The device may be used with or without the roller *r*, and the proportions of the parts and 25 their relationship as respects distance may be varied to suit circumstances.

The shank *t* of the roller-support is preferably made as or to possess the properties of a spring, so as to readily yield to pressure. 30 This is a matter of importance, since it adds in a desirable manner to the flexibility between the crayons and the parts by which they are manipulated, a matter of much importance to the user of the device.

Having thus explained the nature of the invention and described a way of constructing and using the same, though without attempting to set forth all of the forms in which it 35 may be made or all of the modes of its use, 40 it is declared that what is claimed is—

1. A staff-marker comprising a suitable stock or base, a series of flat elongated flexible arms secured to said stock, said arms being provided near their outer ends with resilient 45 clips or fingers bent up and offset from said arms for retaining crayons, substantially as described.

2. A staff-marker comprising a suitable stock, a series of elongated resilient arms pivoted on said stock to swing toward or away 50 from each other while held normally against easy displacement from their adjusted positions, said arms being provided with means for detachably holding crayons substantially as described.

3. A staff-marker comprising a suitable

base, a series of resilient arms pivoted to said base, said arms having clamping-fingers for holding crayons, and a series of stops to limit the pivotal movement of said arms, substantially as described. 60

4. A staff-marker comprising a base member or head to permit the arms to be brought nearer or farther from each other, as desired, a series of resilient arms pivotally secured to 65 said base, said arms being provided near their outer ends with resilient fingers, said fingers having their ends flared to receive crayons, substantially as described.

5. A staff-marker or ruling device comprising a stock or head, and a plurality of inherently-resilient crayon-holding arms extending therefrom, and pivoted thereto at their upper ends by means of binding-screws. 70

6. A staff-marker or ruling device comprising a stock or head, and a plurality of inherently-resilient crayon-holding arms extending therefrom, certain of said arms being adjustable to vary the space therebetween. 75

7. A staff-marker comprising a suitable stock or base, a series of elongated flexible arms secured to said stock, said arms being provided near their outer ends with resilient clips or fingers suitable for retaining crayons, combined with a yieldingly-mounted rest and 80 guiding-roller *r*, as explained.

8. The combination, with the crayon-holder having a plurality of resilient crayon-holding fingers, of a roller, its journal-pins, and a resilient frame for connecting the roller with 85 the stock or handle of the device, said frame being provided with bearings for the journal-pins of the roller, substantially as described. 90

9. A ruling device or marker comprising a base or stock, a series of resilient crayon-holding arms secured to said base, a pair of resilient arms secured to said base and provided at their outer ends with bearings, a bearing-roller mounted to rotate in said bearings and 95 serving to guide and steady the movement of the marker when in use, substantially as set forth. 100

In testimony whereof I have signed my name to this specification, in the presence of 105 two subscribing witnesses, this 26th day of October, A. D. 1898.

W. LAWRENCE MURPHY.
